UNITED STATES PATENT OFFICE.

ELMER C. RAUCH, OF COEUR D'ALENE, IDAHO.

SPARK-PLUG.

1,098,637.

Specification of Letters Patent.

Patented June 2, 1914.

Application filed September 11, 1912. Serial No. 719,878.

To all whom it may concern:

Be it known that I, ELMER C. RAUCH, a citizen of the United States, residing at Coeur d'Alene, in the county of Kootenai and State of Idaho, have invented a new and useful Spark-Plug, of which the following is a specification.

The present invention relates to improvements in spark plugs, the primary object of 10 the invention being the provision of a novel construction of plug, in which the concentric terminal thereof is composed of a removable carbon pencil, the same being disposed to contact with a surrounding sparking terminal member, thus providing the greatest possible 15 sparking surface, and an exceedingly "rich" spark.

With the foregoing and other objects in view which will appear as the description 20 proceeds, the invention resides in the combination and arrangement of parts and in the details of construction hereinafter described and claimed, it being understood that changes in the precise embodiment of the 25 invention herein disclosed can be made within the scope of what is claimed without departing from the spirit of the invention.

In the drawings—Figure 1 is a vertical central sectional view through a spark plug 30 made according to and embodying the present invention. Fig. 2 is a section taken on line 2—2 of Fig. 1. Fig. 3 is a view similar to Fig. 1 of a modified form of spark plug.

Referring to the drawings, and more particularly to Figs. 1 and 2, the numeral 1 designates the metallic plug body the upper end of which is in the form of a head and the lower end 2 of which is reduced exteriorly screw threaded for engaging the 35 plug socket of an internal combustion engine. The body is provided with a longitudinal bore or channel 6 therethrough, the lower end of which is counter bored as at 3, and threaded as at 3'

45 Fitting within the bore 6 of the member 1 is an insulating bushing or tube 7, the same being provided with the annular collar 8 which seats within the contracted end 5 of the counterbore 3 and which is flush with 50 the annular shoulder 4 formed by the portion 5. A metallic sleeve 9 is threaded into the counterbore 3 and its upper end engages with the collar 5 and shoulder 4 to lock the insulator member 7 in place, as clearly illustrated. The lower end of the metal member 55 or sleeve 9 is provided with an annular in-

turned flange or lip forming an annular sparking terminal.

The metallic sleeve 9 is of uniform diameter throughout its length, and the basal portion of the annular lip or flange 10 is 60 relatively thick, while the free edge of the lip is sharpened and forms an opening coaxial with and larger than the counterbore of the bushing 7.

The insulator member 7 is provided with a longitudinal bore 11 in which is fitted the metallic rod 12, whose upper end is threaded for the reception of the binding screw 14 and whose lower end 15 is disposed within 70 the enlarged portion or counterbore 16 formed in the lower end of the insulator member 7.

The upper threaded end of the rod 12 is threaded within the upper end of the bore 11, to hold the rod 12 against sliding longitudinally, and to permit the rod 12 to be adjusted longitudinally by rotating it. The 75 sparking terminal 17 has its upper end fitted snugly within the counterbore 16, and 80 threadedly receives the lower end of the rod 12. This sparking terminal 17 is in reality a carbon pencil, although it is to be understood that any material may be employed that will produce the desired result, the 85 lower end 18 of the terminal 17 being disposed in co-active sparking relation to the 90 sparking terminal 10 of the member 9.

The carbon pencil or terminal 17 is of 95 uniform diameter throughout its length and 90 has one end portion received snugly by the counterbore of the bushing, while its free end is passed through the opening formed by the lip 10.

In the form of spark plug shown in Fig. 3, the member 19 which corresponds to the member 1 of the spark plug shown in Figs. 1 and 2, is exteriorly threaded and reduced as at 20 for engagement with the plug receiving aperture of an engine, and is provided with the sparking terminal 21 at the lower end thereof. A chamber 22 which corresponds to the chamber of the sleeve 9 of the other form, is provided in the lower end of the member 19, and this member 19 is provided with the concentric bore 23 providing the annular shoulder 24 and the threaded portion 25 open at the upper end of the body 19.

Removably insertible within the member 19 from the upper end thereof and instead of from the lower end as shown in Fig. 1,

is the insulator member 26, which is provided with the lower reduced end 27 which projects within the chamber 22 of the member 19, the intermediate enlargement 28 which fits within the chamber 23 and against the annular shoulder 24, the same providing an annular shoulder at the upper portion thereof for the engagement of the lower end of the locking sleeve 29 which is engageable with the threaded portion 25 of the member 19 and surrounds the upper end of the insulator 26.

Disposed concentrically of and through the insulator member 26 is the terminal rod 30, which has mounted upon its upper end the binding nut 31, while its lower threaded end 32 removably receives the upper end of the concentric terminal 33, said terminal 33 corresponding with the terminal 17 and disposed to have its lower end in sparking relation to the terminal 21.

From the foregoing description, it is evident that with the construction herein set forth, that the insulator member bodily carries the removable sparking terminals 17-33, and that by such arrangement the sparking terminal may be removed in case of "burn-out" or breakage and readily replaced; and also that by reason of the threaded portion at 15-32, the respective terminals may be readily adjusted so as to be placed in the most efficient relation to the sparking terminals 10-21.

What is claimed is:

- 35 1. A spark plug comprising a metallic plug body having a longitudinal bore provided with a counterbore at its lower end, an insulating bushing fitting within the said bore and having its lower end disposed within the said counterbore, the bushing having a longitudinal bore provided with a counterbore at its lower end, a metallic rod fitting within the bore of the bushing, the lower end of the rod being disposed within the counterbore of the bushing, and the upper end of the rod being threaded within the upper end of the bore of the bushing and projecting from the upper end of the bushing, a binding nut engaged on the upper end of the said rod, a sparking terminal comprising a carbon pencil of uniform diameter throughout its length having its upper end fitting within the said counterbore of the said bushing and threaded receiving the lower end of the said rod, and an annular sparking terminal carried by the lower end of the plug body and surrounding the lower end of the said sparking terminal.
- 40 2. In a spark plug, a metallic plug body having a longitudinal bore provided with a counterbore at its lower end, an insulating bushing fitting through the said bore and having its lower end disposed within the

said counterbore, the bushing having a longitudinal bore and a counterbore at its lower end, and having a collar fitting within the upper end of the counterbore of the plug body, a metallic sleeve of uniform diameter throughout its length threaded into the counterbore of the plug body and engaging the said collar, the lower end of the sleeve having an annular inturned lip, the basal portion of the lip being relatively thick and the free edge being sharpened and forming an opening co-axial with and larger than the counterbore of the bushing, a carbon pencil of uniform diameter throughout its length having one end portion received snugly by the counterbore of the bushing and having its other end passed through said opening formed by the lip, a metallic rod passed through the bore of the bushing and having its lower end threaded into the first mentioned end of the carbon pencil, and a binding nut threaded on the upper end of said rod to seat against the upper end of the bushing.

3. In a spark plug, a metallic plug body having a longitudinal bore provided with a counter bore at its lower end, an insulating bushing fitting within the said bore and having its lower end disposed within the said counter bore, the bushing having a longitudinal bore provided with a counter bore at its lower end, and having a collar fitting within the upper end of the counter bore of the plug body, a metallic rod fitting within the bore of the bushing, the lower end of the rod being disposed within the counter bore of the bushing, and the upper end of the rod being threaded within the upper end of the bore of the bushing and projecting from the upper end of the bushing, a binding nut engaged on the upper end of the said rod, a metallic sleeve of uniform diameter throughout its length threaded into the counter bore of the plug body and engaging the said collar, the lower end of the sleeve having an annular inturned lip forming an opening coaxial with and larger than the counter bore of the bushing, and a carbon pencil of uniform diameter throughout its length having one end portion received snugly by the counter bore of the bushing and threaded receiving the lower end of the said rod, the carbon pencil projecting through the said opening formed by the lip.

In testimony that I claim the foregoing as my own, I have hereto affixed my signature in the presence of two witnesses.

ELMER C. RAUCH.
